CLAIM

The ornamental design for a pillow, as shown and described.

DESCRIPTION

FIG. 1 is a front side perspective view of a pillow, showing our new design;

FIG. 2 is a right side view thereof;

FIG. 3 is a front view thereof;

FIG. 4 is a top plan view thereof;

FIG. 5 is a left side view thereof;

FIG. 6 is a rear view thereof; and,

FIG. 7 is a bottom plan view thereof.

The convoluted foam pattern is fragmentarily shown in FIGS. 1, 3, 4, 6, and 7 for ease of illustration and the dashed lines indicate that said pattern extends uniformly throughout the area represented.
